By *Ed. N. Shandor* Atty.

UNITED STATES PATENT OFFICE.

JAMES R. GOODWIN, OF EVANSVILLE, INDIANA; PERCY E. GOODWIN AND WALTER C. GOODWIN, ADMINISTRATORS OF SAID JAMES R. GOODWIN, DECEASED, ASSIGNEES TO THE STEEL SCAFFOLDING COMPANY, OF EVANSVILLE, INDIANA, A CORPORATION OF INDIANA.

ADJUSTABLE POST BRACKET.

Application filed February 13, 1924. Serial No. 692,574.

This invention relates to brackets of that general class which are adapted to be clamped to a post for use in the construction of gas tanks, oil tanks, and other constructions or installations where a bracket of this general character is needed.

The object of my invention is to provide a simple, strong, and durable foldable post bracket of improved construction provided with novel means for attaching it to the post and holding it in any desired position thereon without possibility of accidental slippage or of wobbling but with adaptability for quick and easy adjustment or removal.

The bracket and the clamping or fastening devices thereof are so constructed and arranged that the bracket may be applied to any post of the usual sizes employed in construction work.

My bracket is so constructed that it may be folded into compact arrangement so as to be readily carried about without occupying much space.

In the following specification and the accompanying drawings I have set forth one embodiment of the invention. It will be understood, however, that modifications may be resorted to within the spirit and scope of the invention.

In the accompanying drawings:

Fig. 1 is an elevation of the bracket, applied to a post.

Fig. 2 is a detail plan view partly in section, showing the upper fastenings and clamp.

Fig. 3 is a section on line 3—3, Fig. 1, certain parts being in full lines; and

Fig. 4 is a side view illustrating the manner in which the brackets may be folded.

A fragment of a post such as commonly used in construction of gas tanks, oil tanks, and other scaffolds used for erection purposes, is shown at 1 to illustrate the manner of use of the bracket which is shown applied thereto.

My improved bracket is of metal and is complete and self-contained, ready for attachment to any post such as that shown at

1. The bracket has an arm 2 and a brace 3 which are of angle iron construction for purposes of strength, the two being jointed together on a screw bolt 4. When the bracket is in use, the arm 2 is adapted to support a

plank, it being understood that the plank runs from a bracket on one post to a corresponding bracket on another post in the usual manner.

The arm 2 and brace 3 are detachably and adjustably secured to the post by clamps of the construction shown in Figs. 2 and 3.

The slots 15 are provided in the arm 2 and brace 3, and the series of holes 16 are provided in brace 3 to afford adaptability for adjustment of the clamp bolts 6. The nuts 9 are employed.

The bolts 6 are J-shape, being provided with hooks 7' which are adapted to snugly embrace the horizontal webs of the arm 2 and brace 3 in the manner clearly shown in Figs. 2 and 3 and there are provided the upper and lower clamp plates 17 and 18 which lie on the opposite side of the post 1 from the arm and brace, respectively. The shanks of the J-shaped bolts 6 lie against the webs of the angle-irons which their hooks 7' embrace, thus strengthening said shanks and preventing slippage of the hooks 7'.

The left hand upper bolt 6 passes through a hole in the vertical web of the arm 2. The right hand bolt 6 passes through a slot in the upper plate 17.

The left hand bolt 6 for the brace 3 passes through a slot 19 and the right hand bolt for the brace 3 passes through a hole 20.

The plates 17 and 18 afford wide surfaces to clamp against the face of the post and they also provide broad bearing surfaces for the nuts 9 to work against. The vertical webs of the arm 2 and brace 3 bear firmly against the post.

The clamp bolts being disposed transversely of the arm and brace and there being two in each instance, the bracket will support very heavy weights as the bolts cannot give way unless they are completely sheared off, and because the weight supported by the bracket is applied cross-wise of the bolts, instead of lengthwise thereof, there is no danger of the threads of the bolts being stripped by the weight.

The hooks 7' not only serve as heads for the bolts but they prevent any turning or twisting of the bolts. Inasmuch as the bolts 6 pass through a hole in one web of the bracket and hook over the other web there-

of as well as lie against the web which is embraced by the hook, the bracket is firmly held in position against the post, without any possibility of wabbling.

5 I claim:

In a post bracket, the combination with an arm of angle-iron, of a brace therefor which is of angle-iron, and means for independently securing the arm and the brace to 10 a post, comprising in one instance J-shaped screw bolts whose shanks pass through one

web of the brace and in the other instance J-shaped screw bolts whose shanks pass through one web of the arm, said screw bolts each having a hook at one end and a 15 nut at the other end, the hooks snugly embracing a web of arm and brace and the shanks lying against the webs embraced by the hooks, and clamp plates through which the nut-carrying ends of the bolts pass. 20

In testimony whereof I affix my signature.

JAMES R. GOODWIN.
